Primary Examiner — Cynthia M Chin*Assistant Examiner* — Sheryl Lane(74) *Attorney, Agent, or Firm* — Foley & Lardner LLP(57) **CLAIM**

We claim the ornamental design for a hand pruner, as shown and described.

DESCRIPTION

FIG. 1 is a perspective view of a hand pruner showing the claimed design.

FIG. 2 is a back elevation view of the claimed design of FIG. 1.

FIG. 3 is a front elevation view of the claimed design of FIG. 1.

FIG. 4 is a top view of the claimed design of FIG. 1.

FIG. 5 is a bottom view of the claimed design of FIG. 1.

FIG. 6 is a left side elevation view of the claimed design of FIG. 1; and,

FIG. 7 is a right side elevation view of the claimed design of FIG. 1.

The ornamental design which is claimed is shown in solid lines in the drawings. The broken line showing of the hand pruner is for the purpose of showing portions of the hand pruner and forms no part of the claimed design.
